UNITED STATES PATENT OFFICE

WILLIAM E. BRINDLEY, OF WILKINSBURG, PENNSYLVANIA, ASSIGNOR TO WESTINGHOUSE ELECTRIC & MANUFACTURING COMPANY, A CORPORATION OF PENNSYLVANIA

SOUND AMPLIFYING SYSTEM

Application filed March 20, 1930. Serial No. 437,378.

My invention pertains to sound amplifying systems and more particularly to a system capable of use as a public address system or as an advertising medium.

5 In a system as referred to above, an energy-translating device must be used which is capable of reproducing voice and music with a high degree of amplification. The elec-
10 trodynamic speaker, of all known types of loud speakers, is best suited for the purpose, since it can amplify sounds to a high degree without introducing distortion and, in addition, is capable of reproducing notes and tones over a wide band of frequencies with a
15 substantially uniform degree of amplification. A speaker of this type operates by reason of the reaction between the fluxes produced in two coils, one of which is supplied with a constant unidirectional potential and
20 the other of which is supplied with a variable potential at audio frequency. A speaker of this type, normally, requires two separate sources of energy, one to supply the direct current and the other to supply the audio
25 frequency current and two separate transmission channels leading to the loud speaker coils heretofore have been considered necessary.

30 In a public address system or an advertising device where the loud speaker is located at a distance from the sources of energy, the use of a dynamic loud speaker proves to be both expensive and inconvenient in that two transmission channels are required and, in
35 addition, the capacity between the long leads of the transmission channels provides by-paths for the audio frequency currents, thereby reducing the efficiency of the system.

40 One object of my invention is to provide a system of the type referred to above, where-
in the energy required by a dynamic loud speaker shall be supplied over a single transmission channel.

45 Another object of my invention is to pro-
vide a system wherein the current from an A. C. source and the current from a D. C. source may be superposed on a common trans-
mission medium and, subsequently, separat-
50 ed to operate a dynamic speaker, thereby

eliminating, to a great extent, the distributed capacity inherent in prior known systems.

A further object is to provide a system whereby A. C. and D. C. currents to a dynamic speaker may be supplied from the
55 space discharge current of a thermionic device.

An additional object of my invention is to provide a simple and inexpensive system wherein a loud speaker of the dynamic type
60 may be conveniently located at a distance from its source of energy.

A more specific object is to provide an advertising device wherein a captive balloon may be, advantageously, utilized to support a loud speaker of the dynamic type.

Other objects and features of my invention will be disclosed in the following description taken in conjunction with the drawing wherein the figure represents a specific embodiment
70 of my invention as applied to an advertising device.

75 A sound amplifying system constructed according to my invention comprises a captive balloon, not shown, from which is suspended or otherwise supported, a loud speaker of the dynamic type. The anchoring means for the balloon comprises a conductive cable, said cable in combination with an insulated wire extending from the ground to the balloon, constituting the sole means for conveying energy to the dynamic loud speaker, as will be more fully explained in the following description.

80 The source of audio-frequency current is constituted by a disc 1 adapted to actuate a pick-up device 2 which is connected in series with a battery 3 and a primary of a transformer 4, thereby modulating the current in
85 that circuit. This modulated current will be amplified by means of the audio-frequency amplifier and subsequently impressed on the output circuit of the transformer 5.

90 The output of said transformer is connected to two contacting devices 6 and 7 which are adapted to ride upon the edges of two rotatable conducting spindles 8 and 9, one of said spindles 9 carrying a conducting cable 11 which is adapted to function as an anchor
100

cable of a captive balloon, the other of said spindles carrying a winding preferably of insulated wire 12 which is in electrical connection with said spindle, the free portion 5 of said winding being electrically connected to the primary of the transformer 13 and to the D. C. coil 14 of the loud speaker 15. An insulator 16 serves to maintain the wire and cable in spaced relation. The return paths 10 through said primary and said D. C. coil terminate in an electrical connection 17 to the anchor cable of the balloon, the output of the transformer serving to supply the energy necessary to energize the audio-fre- 15 quency coil of the loud speaker. The cable and wire constitute the sole means for conveying energy to both the D. C. and A. C. coils of the loud speaker.

A direct-current supply for energizing the 20 D. C. coil of the loud speaker is disclosed as comprising a full wave rectifier 18 in combination with an A. C. source of supply, the output of which is connected to the contactors 6 and 7 thereby impressing the D. C. output 25 also upon the transmission channel constituted by the cable 11 and the wire 12. The condenser 19 in the output circuit of the transformer 5 and the condenser 20 in the input circuit of the transformer 13 function 30 to prevent the direct current from entering the alternating-current circuits and, in like manner, the choke coils 22 and 23 in the output circuit of the rectifying means and the choke 25 in the input circuit of the D. C. coil 35 serve to lock out the alternating currents from the direct-current circuits, thus causing said circuits to operate as filter circuits.

It will thus be seen that I have provided a 40 system wherein an alternating current and a direct current are superposed upon a common or identical transmission channel and, subsequently, separated to supply the direct-current coil and the alternating-current coil of a dynamic speaker with their corresponding 45 currents.

It will be obvious that a microphone might 50 be used in place of the pick-up mechanism for the purpose of broadcasting speech, and it is within the contemplation of my inven- 55 tion to do this.

Although I have disclosed a separate source 60 of direct current to energize the D. C. coil of the loud speaker, it is within the scope of my invention to utilize the D. C. component 65 of the space discharge current of the audio-frequency amplifier for the same purpose in a manner suggested in a prior application of mine, Serial No. 251,901.

My invention as described above possesses 70 all the advantages set forth in the objects of my invention, and while I have described the invention as embodied in an advertising device, it can be used equally as well for other 75 purposes, such as public address systems, etc.,

and I do not desire to be limited to the specific disclosure except insofar as the prior art requires it.

I claim as my invention:

1. In a sound amplifying system, means for 70 producing a variable current, means for producing a direct current, an energy translating device comprising means responsive to said variable current and means responsive to said direct current, a support for said energy translating device, and means for conveying said currents to said energy translating device, said conveying means comprising a common transmission channel, at least one conductor of said transmission channel forming an anchoring cable in said system for said support. 75

2. In a sound-amplifying system, an energy-translating device of the electrodynamic type, means for supporting said device, cable means for anchoring said supporting means, a source of alternating current energy, a source of direct current energy, a conductive path from said sources to said energy-translating device, said cable anchoring means and said conductive path comprising the sole 80 means whereby energy may be transmitted from said source to said energy-translating device. 85

In testimony whereof, I have hereunto subscribed my name this 17th day of March, 1930. 90
